Atty's.

UNITED STATES PATENT OFFICE.

LEON S. WOLFE, OF WASHINGTON, DISTRICT OF COLUMBIA, ASSIGNOR TO THE J. M. NEY COMPANY, OF HARTFORD, CONNECTICUT.

LINGUAL BAR.

Application filed September 9, 1921. Serial No. 499,535.

To all whom it may concern:

Be it known that I, LEON S. WOLFE, a citizen of the United States, and a resident of the city of Washington, in the District of Columbia, have invented certain new and useful Improvements in Lingual Bars, of which the following is a specification.

My invention relates to lingual bars for artificial dentures, and particularly to the portions thereof intended to be embedded and retained in the vulcanite portions of the denture; and consists in giving to said portions of the lingual bars a certain configuration and variable cross section, the surfaces having projections thereon whereby the said portions of the bars are most firmly and efficiently retained in place within the portions of the denture made of vulcanite or other similar material.

20 Referring to the drawings:—

Figure 1 is a plan view of my bar.

Figure 2 is a lateral elevation of the retaining ends or surfaces.

Figures 3, 4 and 5 are lateral elevations of 25 different retaining surfaces provided in the end of the bar.

The lingual bar 10 is of the usual substantially lenticular or flattened oval cross section, having the usual curved portion 11 from which extend distally the arm portions 12, which are provided with retaining ends 13 adapted to be embedded and retained in the vulcanite saddle portion of the denture (not shown). In the modification illustrated in Figs. 1 and 2, the ends 13, for example, are each provided with serrations or teeth 14 projecting outwardly and mesially from the edge of the end 13. The points 14 appear on two opposite edges of the ends 13 of the bar, the two surfaces lying between these being formed to have transverse serrations forming depressions 15 and elevations 16. It may occasionally be desirable for considerations of space, etc., to alter the position of the points 14, and these may be bent laterally, or otherwise, with any suitable tool such as a pair of pliers; and such bending will not be detrimental, but will give added strength to the joint between the

retaining ends of the bar and the saddle 50 portions.

In the modification of Fig. 3 the retaining portions consist of a series of small pyramids 21, preferably truncated, so as to have small apical surfaces 22, the series of pyramids extending over the entire lateral surfaces of the retaining ends, and the outer row thereof forming the edge projections 23. It will thus be seen that with my invention, the retention of the lingual bar in the saddle 60 portion is assured without in any way sacrificing the strength of the bar.

Fig. 4 shows a form of construction in which the retaining surface 13 of the bar is provided with an opening, as at 24, and in 65 which the longitudinal edges of the opening are provided with serrations 25. In the modification of Fig. 5 the retaining end is bifurcated, each bifurcation 26 being provided with edge serrations 25. The lateral 70 surfaces between the edge serrations of both these forms may be provided with additional retaining surfaces such as the transverse serrations 15, 16 of Fig. 2 or the truncated pyramids 22 of Fig. 3, or the like.

Having fully described my invention, what I claim is:—

1. A lingual bar, the ends thereof being provided with a retaining surface comprising a plurality of mesially projecting serrations.

2. A lingual bar, the ends thereof being provided with a retaining surface comprising a plurality of mesially projecting edge serrations.

3. A lingual bar, the ends thereof being provided with retaining surfaces comprising a plurality of mesially projecting serrations and transverse serrations.

4. A lingual bar, the ends of which are 90 provided with retaining surfaces, said surfaces being provided with an opening and with projecting edge serrations.

5. In a lingual bar, bifurcated retaining ends, the bifurcations being provided with 95 a plurality of projecting edge serrations.

LEON S. WOLFE.
